[57] CLAIM

The ornamental design for an x-ray irradiation unit for a dental x-ray diagnostics installation, as shown and described.

DESCRIPTION

FIG. 1 is a perspective view of an x-ray irradiation unit for a dental x-ray diagnostics installation, the broken line showing of the wall adapter and multi-element bracket is for illustrative purposes only and forms no part of the claimed design;

FIG. 2 is a front elevational view of the x-ray irradiation unit illustrated in FIG. 1;

FIG. 3 is a side elevational view of the right side of the x-ray irradiation unit of FIG. 2;

FIG. 4 is a side elevational view of the left side of the x-ray irradiation unit of FIG. 3;

FIG. 5 is a back elevational view of the x-ray irradiation unit of FIG. 1;

FIG. 6 is a top plan view of the x-ray irradiation unit of FIG. 2; and,

FIG. 7 is a bottom plan view of the x-ray irradiation unit of FIG. 2.
